UNITED STATES PATENT OFFICE.

ROBERT ECKERT, OF DELEMONT, SWITZERLAND.

DEVICE FOR SECURING CHIGNONS TO BOBBED HAIR.

Application filed March 7, 1928, Serial No. 259,876, and in Switzerland October 7, 1927.

This invention has for its object a device for securing a chignon to bobbed hair.

According to the present invention the device comprises a supporting member curved according to the form of the rear of the head and provided with one or more gripping devices adapted to be threaded upwards in bobbed hair and secure the supporting member to the hair and a frame member adapted to carry the chignon pivotally mounted on the supporting member in such a manner as to be capable of being turned downwards so as to permit the securing device to be placed in position without disarranging the bobbed hair or the form of the chignon and raised and secured on the supporting member after the latter has been secured in position in the bobbed hair. Such a device permits a chignon to be applied to bobbed hair very readily and—what is very important—with-out disarranging the hair of the person, or the form of the chignon, which can be dressed and mounted previously, that is to say, before the application of the device to the hair.

One embodiment of the invention in which the supporting member of the chignon securing device is adapted to be secured to the hair by means of two gripping devices, is described by way of example with reference to the accompanying drawings in which:—

Figure 1 is a view of the device in use; Figure 2 is a rear elevation view of the device, with the chignon removed.

Figure 3 is a view showing a transverse section through the assembled device with the chignon removed.

Figure 4 is a plan view, with the chignon indicated by hatched lines;

Figure 5 is an elevational view of the frame member upon which the chignon is adapted to be mounted.

Figures 6 and 7 are views illustrating in detail the above mentioned gripping devices.

Referring now to the drawings the device comprises a supporting member A consisting of a bar-like piece curved according to the form of the rear of the head and having at its upper edge two lugs *a*, on which gripping devices B are mounted. The gripping devices are each in the form of a small long-toothed comb, the teeth *b* of which, are secured at their lower ends in a

resilient metallic member *b*¹ in the form of a stirrup (Figures 6 and 7). The arms of the stirrup *b*¹ are guided on a member *a*¹ secured to the lug *a*, of the bar A, a head *a*² 60 being provided at one extremity of the member *a*¹, the other extremity of which carries a small lever *b*² pivotally mounted at *b*³ and having a projection constituting a cam, adapted, when the lever *b*² is turned 65 in a clockwise direction (Figure 6) to act on the stirrup *b*¹, so as to deform the latter and release or disengage the teeth *b* from one another. In this position of the teeth the latter can be threaded upwards in 70 bobbed hair, sliding against the skin of the head, the hair being taken up between the teeth of the comb. The member A being thus placed in position, the levers *b*² are 75 lifted thus permitting the stirrups *b*¹ to be straightened and the teeth *b* to come together and grip the hair, the member A being thus firmly held in place.

On the supporting member A a base member for supporting the chignon is 80 pivotally mounted at *c*. The base member consists of a curved frame D, a canvas frame D¹ being adapted to be connected to the frame D in such a manner as to be removable therefrom, the chignon being 85 adapted to be mounted on the frame D¹ before the latter is secured to the frame D. Screws *d* on one of frames D, D¹ and notches *d*¹ on the other frame (Figures 2 and 5), together with a clip *d*² serve for 90 securing the frames together, but other securing devices may be utilized. The frames D, D¹ thus secured together, are adapted to be secured in an upright position on the supporting member A by a spring clip *f* 95 provided on the member A and adapted to engage with the unit constituted by the two frames D, D¹.

The apparatus is used as follows:—

The chignon having been mounted on the 100 canvas frame D¹ the latter being separated from the frame D for this purpose, the frame D¹ is then secured to the frame D so as to constitute a unit which is turned 105 downwards about the pivots *c* and after the teeth *b* of the stirrups *b*¹ have been released by depressing the levers *b*², as shown in Figure 7, the combs are threaded upwards in the bobbed hair until the supporting member A is in the required position, 110 whereupon the levers *b*² are raised thus permitting the teeth *b* to close together on the

hair which has been taken up between the teeth and hold the member A firmly in place in the hair. The member A can thus be placed in position without disarranging the bobbed hair, or the form of the chignon. After the member A has been secured in position the unit comprising the frames D, D¹ and the chignon is raised by rotation about the pivots e until it is held in its raised position against the supporting member A by the spring clip f. Two pins may be introduced from the sides into the hair under the gripping devices in order to assure the maintenance of the chignon in position.

The supporting member A and the frames D, D¹ are preferably made of a light metal, such as aluminum or an alloy of aluminum, but may consist of any suitable material.

The invention is not limited to the embodiment thereof described with reference to the drawings. For example, instead of two gripping devices, one gripping device only in the form of a comb may be employed. Moreover, the chignon could be mounted on one frame only pivotally mounted on the supporting member in such a manner as to be able to be removed therefrom for the purpose of mounting the chignon.

What I claim is:—

1. A device for securing chignons to bobbed hair, comprising a supporting member curved according to the rear of the head, means on said supporting member to secure same to bobbed hair, a movable frame adapted to carry the chignon and pivotal connection means to pivotally connect said frame to the supporting member, for the purpose specified.

2. A device for securing chignons to bobbed hair, comprising a supporting member curved according to the rear of the head, means on said supporting member to secure same to bobbed hair, a movable frame adapted to carry the chignon and interconnection means between said supporting member and chignon carrying frame adapted to allow removal thereof from the supporting member, for the purpose specified.

3. A device for securing chignons to bobbed hair, comprising a supporting member curved according to the rear of the head, comb-like gripping means on said supporting member to secure same to bobbed hair, a

movable frame adapted to carry the chignon and pivotal connection means to pivotally connect said frame to the supporting member, for the purpose specified.

4. A device for securing chignons to bobbed hair, comprising a supporting member curved according to the rear of the head, comb-like gripping means thereon to secure the supporting member to bobbed hair, said gripping means having long gripping teeth, a resilient piece carrying same and an actuating member thereon to produce deformation or resetting of said resilient piece and thereby a release or engagement of the gripping teeth, a movable frame adapted to carry the chignon and pivotal connection means to pivotally connect said frame to the supporting member, for the purpose specified.

5. A device for securing chignons to bobbed hair, comprising a supporting member curved according to the rear of the head, comb-like means on said supporting member arranged to be threaded upwards in bobbed hair for securing the supporting member thereto, a movable frame adapted to carry the chignon and pivotal connection means to pivotally connect said frame to the supporting member, for the purpose specified.

6. A device for securing chignons to bobbed hair, comprising a supporting member curved according to the rear of the head, means on said supporting member to secure same to bobbed hair, a movable frame adapted to carry the chignon and pivotal connection means to pivotally and removably connect said frame to the supporting member, for the purpose specified.

7. A device for securing chignons to bobbed hair, comprising a supporting member curved according to the rear of the head, means on said supporting member to secure same to bobbed hair, a movable frame adapted to carry the chignon and pivotal connection means to pivotally connect said frame to the supporting member, in order to allow of turning downwards and upwards of said frame for chignon applying purposes, fastening means being provided to secure said frame in its upward position to the supporting member.

In witness whereof I have hereunto signed my name this 23rd day of February, 1928.

ROBERT ECKERT.
